UNITED STATES PATENT OFFICE

2,393,001

CUTTER CHAIN

Leon E. Simmons, Claremont, N. H., assignor to
 Sullivan Machinery Company, a corporation of
 Massachusetts

Application August 9, 1943, Serial No. 497,923

5 Claims. (Cl. 262—33)

This invention relates to cutter chains and more particularly to an improved bit stop for a cutter bit carrying cutter chain especially designed for use in the cutting of coal.

An object of the present invention is to provide an improved cutter chain. Another object is to provide an improved cutter chain having improved bit stops for the cutter bits on the blocks. A further object is to provide an improved bit stop for limiting the inward movement of the bit shank in the block socket. Yet another object is to provide an improved detachable bit stop which is loosely positioned between adjacent strap links beneath the block socket for limiting the inward movement of the bit shank in the socket. A still further object is to provide an improved bit stop which is relatively simple in design and structure and which may be readily assembled on a conventional cutter chain. Other objects and advantages of the invention will, however, hereinafter more fully appear.

In the accompanying drawing there is shown for purposes of illustration one form which the invention may assume in practice.

In this drawing:

Fig. 1 is a view in longitudinal vertical section taken through a section of a cutter chain with which an illustrative form of the improved bit stop is associated.

Fig. 2 is a cross sectional view taken substantially on line 2—2 of Fig. 1.

Fig. 3 is a horizontal sectional view taken substantially on line 3—3 of Fig. 1.

Fig. 4 is a perspective view of the bit stop.

Fig. 5 is a side elevational view of the bit stop.

Fig. 6 is an end elevational view of the bit stop.

In this illustrative embodiment of the invention the improved bit stop, generally designated 1, is shown associated with a cutter bit carrying cutter chain of a conventional design. The cutter chain includes a chain block 2 pivotally connected at 3 to strap links 4. The chain block has a lateral lug 5 provided with a socket 6 for the reception of a cutter bit 7. This cutter bit is of the single pointed shanked type and has a cutting portion 8 and an integral shank 9, the latter being received in the socket 6 of the block lug. The chain block has parallel side portions 10, 10 provided with lateral gibbs 11 adapted for the reception in the guideway of a conventional cutter bar. The strap links project inwardly between the side portions 10 of the chain block and have curved ends 12 spaced apart to provide a space 13 into which the tooth of a chain drive sprocket is adapted to enter so that the sprocket

tooth may engage a curved end of a strap link to drive the chain. The block lug has a threaded opening 14 in which a set screw 15 is threaded and this set screw, when tightened, engages the bit shank firmly to hold the cutter bit in cutting position on the block. The block socket 6 enters at its bottom the tooth space 13 between the link-ends, and, if no stop were provided, the bit shank would be free to drop down too far into the tooth space 13 and so to interfere with proper engagement of the sprocket tooth with the link.

In this improved construction, the bit stop 1 is arranged in the tooth space 13 between the adjacent ends of the strap links to limit inward movement of the bit shank in the block lug socket. This stop may assume various forms and is herein preferably in the form of a metal strip having enlarged end portions 16 which extend substantially the full distance between the inner surfaces 15 of the side portions 10 of the block in the manner shown in Fig. 3. This metal strip is suitably bent into shape and has its end portions curved at 17 to rest against the curved upper portions of the adjacent ends of the strap links. The sides 25 of the bit stop are preferably cut away or recessed at 18 to provide lateral spaces through which dirt or cuttings may freely pass. The sides of the side portions 10 of the chain block are apertured at 19 to permit discharge of dirt 30 or cuttings from the tooth space 13 between the link-ends.

It will thus be seen that the bit shank 9, when it is inserted in the block socket 6, may drop down until its lower end engages the narrow bridge portion 20 of the bit stop. By limiting the inward movement of the bit shank within the bit socket, undesired entry of the shank into the sprocket tooth space 13 is prevented, and also the gauge of the bit with respect to the block may be predetermined. Engagement of the sides of the enlarged ends 16 of the bit stop with the inner side surfaces of the parallel side portions 10 of the block and with the curved link-ends 12 holds the bit stop against displacement, while permitting some freedom of movement of the stop. The bent piece of metal from which the stop is formed has some inherent resiliency, so in the event dirt or cuttings should pack in the sprocket tooth space, the stop would yield slightly, reducing the possibility of breakage or distortion of the stop.

As a result of this invention an improved detachable bit stop is provided which is of a simple and inexpensive design, and which may be readily applied to a conventional cutter chain without modification. Since the bit stop is loosely posi-

tioned in the block between the link-ends, it may be readily inserted into position and easily removed. Due to the novel design of the bit stop, free flow of dirt or cuttings past the same is possible and the stop, being of resilient material, may bend slightly in the event the sprocket tooth space in the block becomes packed with dirt or cuttings. In the improved design, expensive rigid bit stop parts welded or otherwise permanently secured to the block are avoided. Other advantages of the invention will be clearly apparent to those skilled in the art.

While there is in this application specifically described one form which the invention may assume in practice, it will be understood that this form of the same is shown for purposes of illustration, and that the invention may be modified and embodied in various other forms without departing from its spirit or the scope of the appended claims.

What I claim as new and desire to secure by Letters Patent is:

1. In a cutter chain, a chain block having a bit receiving socket, strap links pivotally connected to said block, and a detachable bit stop loosely positioned in said block between and resting against the adjacent ends of the strap links for limiting inward movement of a bit in said block socket.
2. In a cutter chain, a chain block having a bit receiving socket and spaced apart parallel side portions, strap links pivotally connected to said block and projecting between said side portions, the inner adjacent ends of the links being spaced apart to provide a space, and a detachable bit stop positioned in said space between said side block portions and the adjacent link-ends, said stop guided between said side portions and resting against said link-ends and serving to limit inward movement of a bit in said block socket.
3. In a cutter chain, a chain block having a

bit receiving socket, chain elements pivotally connected to said block, said block and chain elements being so arranged that a sprocket tooth receiving space is formed within the block between the adjacent ends of said chain elements, said socket communicating at its lower end with said space, and a detachable bit stop loosely mounted in said space above the sprocket tooth receiving portion thereof and beneath said socket and resting against the adjacent ends of said chain elements for limiting inward movement of a cutter bit in said socket.

4. In a cutter chain, a chain block having a bit receiving socket and spaced apart side portions, strap links pivotally connected to said block and projecting between said side block portions, the inner adjacent ends of said strap links being curved and spaced apart to provide a sprocket tooth receiving space, and a detachable bit stop disposed in said space between said side block portions and said adjacent link-ends and loosely supported by said strap links, the ends of said stop being curved to conform to the curved ends of said strap links, said stop serving to limit inward movement of a bit in said block socket.

5. In a cutter chain, a chain block having a bit receiving socket and spaced apart side portions, strap links pivotally connected to said block and projecting between said side block portions, the inner adjacent ends of said strap links being curved and spaced apart to provide a sprocket tooth receiving space, and a detachable bit stop disposed in said space between said side block portions and said adjacent link-ends, the sides of said stop being parallel and the ends of said stop being curved to conform to the curved ends of said strap links, and said curved ends of said stop resting against said ends of said links and the sides of said stop being guided by said side block portions, said stop serving to limit inward movement of a bit in said block socket.

LEON E. SIMMONS.
